ARTHUR B. FOOTE, OF GRASS VALLEY, CALIFORNIA.

CAM FOR STAMP-BATTERIES.

1,152,161.

Specification of Letters Patent. Patented Aug. 31, 1915.

Application filed September 15, 1914. Serial No. 861,878.

To all whom it may concern:

Be it known that I, ARTHUR B. Foote, a citizen of the United States, residing at Grass Valley, in the county of Nevada and 5 State of California, have invented new and useful Improvements in Cams for Stamp-Batteries, of which the following is a specification.

This invention relates to stamp batteries 10 and particularly to cams thereof.

It is an object of this invention to provide an improved cam designed to lift the stem without shock from a state of rest and to impart to the stem a constantly accelerating velocity and momentum to carry it to a height sufficient to produce a resultant drop of predetermined length.

Another object of the invention is to so 20 design the cam that the life of the battery elements is greatly conserved by materially reducing vibrations, and which operates upon the parts in such a manner that the slipping of tappets and separation of shoes from the stems is eliminated, thus saving a 25 great deal of valuable operating time and costly labor.

A further object is to provide a cam of 30 such contour that the speed of revolution of the cam shaft may be considerably increased with a resultant increase in the number of 35 drops of stamp per minute and without the serious deterioration of parts commonly incident to battery parts as now generally in use when speed is increased.

The invention consists of the parts and 40 the combination and construction of parts as hereinafter more fully described and claimed, having reference to the accompanying drawings, in which—

Figure 1 is a side elevation of a battery 45 stem with a tappet, and a cam on the shaft. Fig. 2 is a view of the cam and its development.

At 2 is shown a cam shaft perpendicular 50 to which stands a battery stem 3 with a tappet 4 suitably secured thereon. On the cam shaft is secured a cam 5 to which this invention particularly relates.

Battery cams are usually provided with 55 diametrically opposite active surfaces 6 co- active successively with the lower end of the tappet 4, so that during one revolution of the shaft the stem is lifted and dropped twice. Ordinarily the speed of batteries is

95 drops per stem per minute; this being the 55 most economical for wear of parts. My present cam is expressly designed so that the speed of operation may be economically and safely increased to 110 drops per minute, and to greatly eliminate vibration and lessen 60 the noise of cam impact. All this is at once accomplished by giving the active cam surfaces 6 such a form that the cam engages the stem tappet quietly and gradually and subsequently acts to lift the stem with its 65 shoe with a constantly accelerating velocity and momentum. To that end the effective cam surface 6 is laid off with an elevational curvature of suitable angular length about the center of the cam and with a peripheral 70 addendum which constantly increases in height between each degree of the included angle between the root of the curve or cam surface and its apex. This is shown embodied in one form in the diagram where 75 the included angle of the cam surface is 90°. By dividing this into parts of 10° each and projecting radii therefrom the desired curve is readily laid off by marking the radii commencing with the root point *s* and each 80 succeeding one at a point a greater distance from the cam center, as at *a*, *b*, *c*, *d*, *e*, *f*, *g*, *h* and *i*. A constantly accelerated lifting action is had when the radial distance between each of these arbitrary points *a*, *b*, 85 etc., varies increasingly.

I have made and successfully utilized in stamp milling a cam in which the effective curve surfaces are developed as in Fig. 2, in which the addendum, in an arc of 90°, is 90 obtained by pointing of the radii by the concentric arcs *a'*, *b'*, *c'*, *d'*, *e'*, *f'*, *g'*, *h'*, and *i'*; these arcs being struck from a radius *s* and projected from intersections therewith of sines projected from a quarter circle *u*, 95 the radius of which equals the desired height of addendum curve of the cam. The spacing along the projected radius *s* represents distances traversed by the stem in equal intervals of time during a quarter revolution 100 of the cam shaft. This graphically illustrates but one form of curve for a cam designed to lift a stem at a predetermined varying rate of speed. The momentum given the stem will cause it to continue upward movement after leaving the apex of the cam, so that the length of drop will exceed the actual cam lift. 105

Having thus described my invention what I claim and desire to secure by Letters Patent is—

A cam for stamp battery tappets having a surface formed of a series of divisions of successively increasing arcs whereby the tappet is given a constantly increasing rate of speed, the arc of greatest degree terminating in a free apex permitting the tappet 10 to be disengaged from said surface, whereby the momentum given the stem will cause

it to continue upward movement after leaving the apex so that the length of the tappet drop will exceed the actual cam lift.

In testimony whereof I have hereunto set 15 my hand in the presence of two subscribing witnesses.

ARTHUR B. FOOTE.
